UNITED STATES PATENT OFFICE.

FRANK F. WITT, OF ELYRIA, OHIO.

CLOTHES-RACK.

SPECIFICATION forming part of Letters Patent No. 723,114, dated March 17, 1903.

Application filed January 18, 1902. Serial No. 90,347. (No model.)

To all whom it may concern:

Be it known that I, FRANK F. WITT, a citizen of the United States, residing at Elyria, in the county of Lorain and State of Ohio, 5 have invented new and useful Improvements in Clothes-Racks, of which the following is a specification.

This invention relates to clothes-racks for holding and drying clothes and the like; and 10 the aim and purpose of the same is to provide a simple and effective device of this class of a strong and durable construction and which can be compactly reduced when not in use and when arranged for the support of clothes 15 has a great hanging capacity, the plurality of devices upon which the clothes are hung being disposed in such vertical arrangement that the articles on an upper one of such devices will not interfere with a similar device 20 next below the same.

The invention consists in the construction and arrangement of the several parts, which will be more fully hereinafter described and claimed.

25 In the drawings, Figure 1 is a perspective view of the improved rack shown arranged for use. Fig. 2 is a similar view of the rack reduced in compact form. Fig. 3 is a transverse vertical section through the lower portion 30 of the rack. Fig. 4 is a horizontal section through the rack-standard, showing one of the supporting-disks and portions of the arms therein.

Similar numerals of reference are employed 35 to indicate corresponding parts in the several views.

The numeral 1 designates a standard which is preferably cylindrical in form and of any suitable length. The standard 1 is secured 40 in the center of a lower horizontally-disposed base disk or head 2, and at regular intervals above the said disk or head 2 other similar disks 3 are secured to the standard, the uppermost disk being adjacent to the upper terminal 45 of the said standard. The disks 2 and 3 are secured to the standard by U-shaped staples 4, applied inwardly thereover in radial planes and driven into the said standard, as clearly shown by Fig. 4, and between the 50 planes of the legs of the staples vertical apertures 5 are bored or otherwise formed in said disks. Extending radially inwardly from

the periphery of the disks to one side of the plane of the vertical apertures 5 are sockets 6, those in the lower disk 2 being disposed at 55 an upward angle of inclination. The vertical apertures 5 in the successive disks are in staggered relation—that is, the apertures in one disk are out of alinement with the apertures in the disk next above—this disposition 60 of the apertures in the several disks being in regular alternation. Moreover, the sockets 6 are formed in different positions in relation to the said apertures 5. For instance, those in the disk 2 are on the left of said apertures, 65 those in the disk 3 next above on the right of the apertures.

A plurality of arms 7 are employed in connection with the disks or heads 3. These arms, as shown, are angular in cross-section, 70 but may be cylindrical or round, and have tenons 8 at their inner ends to removably fit in either the apertures 5 or sockets 6. The arms 7, which are inserted in the sockets 6 in the lower disk or head 2, are given an outward and downward incline and provide an extended stable base-rest for the entire rack. The arms, which are inserted in the disks 3, are horizontally straight, and in view of the alternate disposition of the sockets 6, as heretofore explained, the arms of one disk or head 75 will be alined with the centers of the spaces between the arms of the disk or head next above, and by this means clothing or other articles disposed or placed on the arms will 80 not touch or interfere with those on the arms next below. The arms are readily removable from the disks or heads, and when it is desired to reduce the rack to compact form the several arms are withdrawn from the sockets 85 6 and are arranged in upright position in the apertures 5, as clearly shown by Fig. 2. When the rack is arranged as shown by Fig. 2, it may be stored within a comparatively small space, and all the parts pertaining 90 thereto will be held in engagement therewith and ready for quick assemblage to change the rack to the form shown by Fig. 1.

A greater or less number of disks or heads 100 may be used than those shown, and the arms may be lengthened and shortened, as desired. Though the rack is particularly intended for receiving articles of clothing it will be understood that it has a general use for display

purposes, and to suit different uses changes in the form, proportions, size, and minor details may be resorted to without departing from the principle of the invention.

5. Having thus fully described the invention, what is claimed as new is—

A clothes-rack comprising a standard having a series of horizontally-disposed disks centrally secured thereto at regular intervals, the 10 disks being fastened to the standard by staples driven radially thereover, the legs of the said staples closely embracing the upper and lower sides of the disks and having regularly-defined spaces, each of the disks between the contiguous staples having vertical 15 openings therethrough close to said legs, and sockets projecting into the same adjacent to

the heads of the staples and to one side of the openings, and a series of arms freely removable in relation to the openings or the sockets 20 and capable of being arranged parallel with the standard when in the openings or in radial relation to the disks when in the sockets, said arms extending outwardly an equal distance from the disks and completely surrounding the latter, the lower disk and its arms forming a base-rest for the rack.

In testimony whereof I affix my signature in presence of two witnesses.

FRANK F. WITT.
